Attorney.

UNITED STATES PATENT OFFICE.

LUDWELL H. GILMER, OF PHILADELPHIA, PENNSYLVANIA, ASSIGNOR TO L. H. GILMER CO., OF PHILADELPHIA, PENNSYLVANIA, A CORPORATION OF NEW JERSEY.

LAMINATED FABRIC.

1,266,789.

Specification of Letters Patent. Patented May 21, 1918.

Application filed November 20, 1917. Serial No. 202,911.

To all whom it may concern:

Be it known that I, LUDWELL H. GILMER, a citizen of the United States, and resident of Philadelphia, in the county of Philadelphia and State of Pennsylvania, have invented certain Improvements in Laminated Fabrics, of which the following is a specification.

My improvements in laminated fabrics are 10 designed to provide, at comparatively small cost, superior brake bands, belts and other articles used for frictional purposes, and they comprise, in the preferred specific form, the combination of cotton webbing and 15 sheeted cork.

In the accompanying drawings, Figure 1 is a perspective view of an article of manufacture embodying a form of my invention; and Fig. 2 is a perspective view of a second 20 form thereof.

The article illustrated in Fig. 1 comprises a section of a woven cotton band or webbing 1 having its edges 1' turned over thereon with a space or channel 2 between them, and a strip of cork 3 laid between the edges 1' in the channel 2, the edges 1' and the strip 3 being secured to the body of the webbing by the rows of stitching 4.

The product is especially adapted for use 30 in making brake bands or linings and belts, as the inlaid cork provides a highly desirable continuous frictional surface and the webbing with its inturned even edges protects the cork as well as provides strength, 35 durability and efficiency at small cost.

The article illustrated in Fig. 2 comprises a section of woven cotton band or webbing 5 on which is laid a continuous sheet or strip of cork 6 of the same width as the webbing, the laminations of webbing and cork being secured together by the rows of 40 stitches 7. This construction provides a relatively more extended frictional surface, at the expense of the greater protection 45 against hard usage which is secured by the form illustrated in Fig. 1.

The form of the device that is most desirable and to be adopted will, in general, depend upon the particular use to which it is to be applied.

Having described my invention, I claim:

1. An article of manufacture for frictional use comprising a strip of webbing having its parallel edges turned over on and secured in contact with its body in 55 laminated relation so as to form a channel between said edges and a frictional material secured in said channel between said edges.

2. An article of manufacture for frictional use comprising a strip of webbing 60 having its parallel edges turned over and sewed to its body so as to form a channel between said edges, and a strip of sheet cork sewed to said body in said channel.

In testimony whereof I have hereunto set 65 my name this 16th day of November, 1917.

LUDWELL H. GILMER
